DESIGN FOR A TELESCOPIC VIEWING STAND OR SIMILAR ARTICLE

Charles A. Brewer, Noroton Heights, Conn.

Application September 10, 1937, Serial No. 71,546

Term of patent 14 years

To all whom it may concern:

Be it known that I, Charles A. Brewer, a citizen of the United States, residing at Noroton Heights, in the county of Fairfield and State of Connecticut, have invented a new, original, and ornamental Design for a Telescopic Viewing Stand or Similar Article, of which the following is a specification, reference being had to the accompanying drawing, forming part thereof.

The design is shown as applied to the support of a binocular of conventional shape.

ing stand or similar article showing the essential features of my new design in full lines; Fig. 2 is an elevation of the design as shown in Fig. 1 but viewed at a right angle to the position from which Fig. 1 is viewed; Fig. 3 is a top plan view with the binocular shown in broken lines in Figs. 1 and 2 omitted for convenience of illustration.

I claim:

The ornamental design for a telescopic viewing stand or similar article, as shown and described.

CHARLES A. BREWER.
